CLAIM

The ornamental design for a necklace, as shown and described.

DESCRIPTION

FIG. 1 is a front right perspective view of a necklace showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear left perspective view thereof.

The chain element is shown with a symbolic break in its length. The appearance of any portion of the article between break lines forms no part of the claimed design.
